UNITED STATES PATENT OFFICE.

CHARLES B. EDWARDS, OF EAST BRAINTREE, AND REDFIELD H. ALLEN,
OF QUINCY, MASSACHUSETTS, ASSIGNORS TO FORE RIVER SHIP & ENGINE
COMPANY, OF QUINCY, MASSACHUSETTS, A CORPORATION OF NEW
JERSEY.

VALVE MECHANISM.

SPECIFICATION forming part of Letters Patent No. 717,559, dated January 6, 1903.

Application filed December 6, 1901. Serial No. 84,906. (No model.)

To all whom it may concern:

Be it known that we, CHARLES B. EDWARDS, residing at East Braintree, and REDFIELD H. ALLEN, residing at Quincy, in the county of Norfolk and State of Massachusetts, citizens of the United States, have invented new and useful Improvements in Valve Mechanism, of which the following is a specification.

The object of this invention is to provide a simple, compact, and durable steam-distribution valve. Said valve is particularly adapted for use in a single direct-acting steam-pump.

The object of the invention, again, is to produce a valve which shall cause the steam-piston to have a continuous motion without any "dead-center," whether the piston is moving at a slow or quick speed and under a light or heavy pressure of steam.

The invention consists in a valve-chest provided with two main inlet-ports and a main exhaust-port, two auxiliary outlet-ports, and an auxiliary exhaust-port, said auxiliary ports entering said valve-chest from a common auxiliary passage, in combination with a main valve controlling said main ports and also provided with a port to connect said exhaust-ports and an auxiliary piston-valve located within said valve-chest, operating said main valve and acting as a switch to alternately control the auxiliary exhaust from opposite ends of said auxiliary passage.

The invention again consists in an auxiliary piston-valve located in a valve-chest and provided with a head at each end thereof, said heads each provided with a recess opening therein from one end of said piston-valve, each of said heads provided with an annular steam-passage extending around the periphery thereof and connected by a passage with said recess.

The invention further consists in the combination and arrangement of parts set forth in the following specification and particularly pointed out in the claims thereof.

Referring to the drawings, Figure 1 is a front elevation of an engine constructed in accordance with our invention and adapted to be connected to a steam-pump, not shown

in the drawings. Fig. 2 is a sectional elevation taken on line 2 2 of Fig. 1 looking toward the left in said figure. Fig. 3 is a longitudinal section taken through the center of the valve-chest upon the line 3 3 of Fig. 2 looking toward the right in said figure and 55 showing the main valve and the auxiliary piston-valve at the extreme right in said figure. Fig. 4 is a view similar to Fig. 3, showing the main valve in the same position as in said figure and the auxiliary piston-valve moved 60 toward the left a distance sufficient to engage said main valve. Fig. 5 is a section similar to Fig. 4, showing the auxiliary piston and the main valve still farther to the left. Fig. 6 is a section similar to Fig. 5, showing 65 the auxiliary piston and main valve in their extreme left-hand positions. Fig. 6^A is a detail longitudinal section taken on line 6^A 6^A of Fig. 2. Fig. 7 is a detail front elevation of the valve-chest. Fig. 8 is a transverse section taken on line 8 8 of Fig. 7. Fig. 9 is a longitudinal section taken on line 9 9 9 of Fig. 8. Fig. 10 is an underneath plan of the valve-chest. Fig. 11 is a detail front elevation of the steam-cylinder. Fig. 12 is a 70 transverse section taken on line 12 12 12 of Fig. 11. Fig. 13 is a side elevation, enlarged, of the auxiliary piston-valve. Fig. 14 is an end elevation of the same. Fig. 15 is an end elevation of the main valve looking in the 80 same direction as in Fig. 2. Fig. 16 is a longitudinal section of the main valve, taken on the line 16 16, Fig. 15, looking toward the left in said figure. Fig. 17 is an underneath plan view of the main valve. 85

Like numerals refer to like parts throughout the several views of the drawings.

In the drawings, 20 is the main steam-cylinder, fast to and supported upon rods 21. The piston 22 is fast to a piston-rod 23, said 90 piston-rod having fastened thereto a cross-head 24, said cross-head 24 having a boss 25 thereon arranged to slide upon one of the rods 21. Said cross-head is connected by a link 26 to a lever 27, pivoted at 28 to the 95 steam-cylinder 20. A sliding block 29 is pivotally connected to a stud 30, fast to the short arm of the lever 27. Said sliding block 29

engages and slides upon a rod 31, having two stop-collars 32 and 33 adjustably fastened thereto by screw-threaded engagement. The rod 31 is pivotally connected at 34 to the lower 5 end of a lever 35, pivoted at 19 to an arm 37 upon the head 38 of the valve-chest 39. The upper end of the lever 35 engages a block 36, fast to the valve-stem 40. The valve-stem 40 slides in the stuffing-boxes 41 42 in the heads 10 38 and 43, respectively, of the valve-chest 39. The valve-chest 39 is secured by bolts 44 to the steam-cylinder 20 and has a cylindrical bore extending from one end to the other thereof and constituting a valve-seat. 15 A cylindrical auxiliary piston-valve 45, fast to the valve-stem 40, fits loosely in the cylindrical bore of said valve-chest. Said auxiliary piston-valve consists of two cylindrical heads 46 and 47, joined together by a cylindrical sleeve 48. Each of the heads 46 and 47 has a recess 49 therein, preferably cylindrical, opening from the end thereof for the purpose of lightening said piston-valve and also to make room for the head at each end 20 of the valve when the auxiliary piston is at the end of its stroke. Each of said heads 46 47 has an annular steam passage or port 50 extending around the outside thereof and connected by passages 51 with said cylindrical 25 recesses.

It will be seen that the auxiliary piston-valve 45 thus divides the interior of the steam valve-chest 39 into three portions—one central steam-chamber 52 between said heads 46 30 and chambers 53 and 54 at each end of said valve-chest. Between the two heads of the auxiliary piston-valve 45 is a main valve 55, having a semicircular face 56, which is formed to fit the interior of the cylindrical 35 bore of the valve-chest 39. Said main valve 40 partially encircles the sleeve 48 of the piston-valve 45 and is provided with a slot 57, extending lengthwise thereof at one side of said valve and engaging the end of a guide- 45 screw 58, which projects inwardly into the said valve-chest and is screw-threaded from the front thereof. (See Fig. 2.)

The main valve 55 has a main port 59 there- 50 in which operates to control the main exhaust- 50 port 60 and the main inlet-ports 61 and 62, formed in the valve-chest 39. The main ex- haust-port 60 passes downwardly from the valve-chest 39 and connects with the ex- haust-port 63 of the steam-cylinder 20, pass- 55 ing out of said steam-cylinder at the outlet 64. The main inlet-ports 61 and 62 pass downwardly from the valve-chest 39 and connect with the main steam-ports 65 and 66, re- spectively, in the steam-cylinder 20. Steam 60 is admitted to the valve-chest 39 in the central chamber 52 at the inlet-opening 67 in the steam-cylinder 20, thence passing through the steam-passage 68, through the port 69, and through the valve-chest inlet-port 70. 65 The steam passes from the central chamber 52 through the balance-ports 71 and 72, re- spectively, at each end of the auxiliary pis-

ton-valve 45 into the end chambers 53 and 54, and thus said auxiliary piston is balanced, except under the conditions hereinafter set forth.

In the valve-chest 39 is also provided an auxiliary exhaust-port 73 and two auxiliary outlet-ports 74 and 75, said ports entering said valve-chest from a common passage 76. 75 In the main valve 55 is provided an auxiliary valve-port 77, leading out of the main valve-port 59 and connecting the main exhaust-port and auxiliary exhaust-port when the main valve is in the position shown in Fig. 5. In 80 Figs. 3, 4, 5, and 6 the auxiliary outlet and exhaust ports, together with the steam-passage 76, are shown in dotted lines for the purpose of illustrating their relative location (in the manner of a diagram) to the auxiliary 85 piston and main valves.

The operation of our improved valve mechanism is as follows: Assuming the various parts to be in the position shown in Figs. 1, 2, and 3, the piston making its downward 90 stroke and having half completed said stroke, the auxiliary piston-valve being at the ex- treme right of its movement, as shown in Fig. 3, and the main valve also being at the ex- treme right, the steam is admitted to the 95 valve-chest as hereinbefore set forth. The auxiliary piston is balanced, as live steam is in the central chamber 52 and in the end chambers 53 and 54. The steam therefore passes from the central chamber 52 through 100 the main inlet-port 62 and through the steam- port 66 to the upper end of the steam-cylinder 20, forcing the piston 22 downwardly, and ex- hausting through the steam-port 65, main in- let-port 61, main valve-port 59, and main ex- 105 haust-port 60 through the exhaust-port 63 and outlet 64. As the piston descends and when it arrives at about one-half stroke, as shown in Figs. 1 and 2, the sliding block 29 engages the collar 32 and through the rod 31 rocks the lever 110 35 upon its pivot 19, drawing the valve-stem 40 toward the left, Fig. 3, and moving the piston- valve from the position shown in Fig. 3 to that shown in Fig. 4, where the piston-valve is just 115 engaging the righthand end of the main valve 55. Upon the continued downward stroke of the piston the main valve and piston-valve move from the position shown in Fig. 4 to that shown in Fig. 5, closing the main inlet-ports 61 and 62 and bringing the auxiliary 120 valve-port 77 in line with the main exhaust- port 60, and thus connecting said main ex- haust-port with the auxiliary exhaust-port 73 and through the auxiliary steam-passage 125 76, port 75, port 50, and passage 51 connect- ing the chamber 54 with the main exhaust- port 60. As soon as the piston arrives at the position shown in Fig. 5, therefore, the exhaust-port being connected with the cham- 130 ber 54, the steam in said chamber will ex- haust through the passage 51, port 50, aux- iliary steam-passage 76, auxiliary exhaust- port 73, auxiliary valve-port 77, main valve- port 59, and main exhaust-port 60. The aux-

iliary piston will thus be unbalanced, exhausting, as described, from the chamber 54, and having the full pressure of steam in the chamber 53 at the other end of said auxiliary 5 piston, and hence said pressure of the steam will drive the auxiliary piston together with the main valve from the position shown in Fig. 5 to its extreme position at the left, as shown in Fig. 6. This last movement of the 10 auxiliary piston and main valves takes place when the piston is at the end of its stroke and carries the valve-stem 40 to its extreme position toward the left and through the block 36 rocks the lever 35 upon its pivot 19, 15 carrying the rod 31 and collars 32 and 33 toward the right, Fig. 1, to the position shown in dotted lines in said figure.

It will be seen by reference to Fig. 6 that the steam is now admitted through the inlet-port 61 to the under side of the piston through the steam-port 65 in the cylinder 20. The piston ascends until the sliding block 29 engages the collar 33, and through connections hereinbefore referred to the valve-stem 40, 25 together with the auxiliary piston-valve 45, is carried to the right from the position shown in Fig. 6 until the same operation is repeated as hereinbefore described in moving the main valve and piston-valve to the left, reversing 30 the inlet and exhaust ports.

It will be seen that by our improved valve mechanism it is impossible to find any point during the movement of the piston up or down which would constitute a dead-center. The valve can be run very slowly or at a great speed with most satisfactory results. The mechanism is simple, durable, and compact and has been demonstrated in a working machine to be entirely practical 40 and satisfactory.

The auxiliary outlet-ports 74 and 75 and auxiliary exhaust-port 73 enter the same auxiliary exhaust-passage 76 from the valve-chest, thus rendering the construction simple, 45 cheap, and easily manufactured.

It will be seen by the construction of the auxiliary piston-valve hereinbefore set forth that said piston-valve may be rotated in the valve-chest without interfering with the operation of the mechanism hereinbefore described, for as a steam passage or port 50 extends entirely around the periphery of the heads 46 and 47 at each end of said auxiliary piston-valve, each of said annular passages 55 being connected by passages 51 with the recess 49, opening from each end of the piston-valve, it is evident that the end chambers 53 and 54 will be connected with the auxiliary outlet-ports 74 and 75, respectively, through 60 said passages 51 and annular passage or port 50 when said annular passage in said auxiliary piston-valve is brought in line with one of said outlet-ports, as hereinbefore described. The angular position of said passages 51 is 65 immaterial to the passage of the steam from said end chambers to said auxiliary outlet-ports. This construction adds to the sim-

plicity and facility of construction and manufacture and assembling of the mechanism, as well as to the accurate operation of the same. 70

Having thus described our invention, what we claim, and desire by Letters Patent to secure, is—

1. In an engine, a valve-chest provided with two main inlet-ports and a main exhaust-port, 75 two auxiliary outlet-ports and an auxiliary exhaust-port, said auxiliary outlet-ports and auxiliary exhaust-port entering said valve-chest from a common auxiliary passage, a main valve controlling said main ports and 80 provided with a single auxiliary port to connect said exhaust-ports, and an auxiliary piston-valve located within said valve-chest, operating said main valve and acting as a switch to alternately control the auxiliary exhaust 85 from opposite ends of said auxiliary passage.

2. In an engine, a valve-chest provided with two main inlet-ports and a main exhaust-port, two auxiliary outlet-ports and an auxiliary exhaust-port, said auxiliary outlet-ports and 90 auxiliary exhaust-port entering said valve-chest from a common auxiliary passage, a main valve controlling said main ports and provided with a single auxiliary port to connect said exhaust-ports, and an auxiliary piston-valve located within said valve-chest and 95 operating said main valve, said auxiliary piston-valve being provided with a central steam-chamber, a steam-passage at each end thereof connecting said central steam-chamber with the ends of said valve-chest and acting as a switch to alternately control the auxiliary exhaust from opposite ends of said auxiliary passage.

3. In an engine, a valve-chest provided with 105 two main inlet-ports and a main exhaust-port, two auxiliary outlet-ports and an auxiliary exhaust-port, said auxiliary outlet-ports and auxiliary exhaust-port entering said valve-chest from a common auxiliary passage, a 110 main valve controlling said main ports and provided with a single auxiliary port to connect said exhaust-ports, and an auxiliary piston-valve located within said valve-chest and operating said main valve, said auxiliary piston-valve being provided with a central steam-chamber, a steam-passage at each end thereof connecting said central steam-chamber with the ends of said valve-chest and acting as a 115 switch to alternately control the auxiliary exhaust from opposite ends of said auxiliary passage, and a port at each end of said auxiliary piston-valve connecting said auxiliary outlet-ports with said valve-chest. 120

4. In an engine, a valve-chest provided with 125 two main inlet-ports and a main exhaust-port, an auxiliary exhaust-passage extending lengthwise of said valve-chest, an auxiliary outlet-port entering said valve-chest from each end of said auxiliary exhaust-passage, 130 and an auxiliary exhaust-port entering said valve-chest from said auxiliary exhaust-passage between said outlet-ports.

5. In an engine, a valve-chest provided with

- two main inlet-ports and a main exhaust-port, an auxiliary exhaust - passage extending lengthwise of said valve-chest, an auxiliary outlet-port entering said valve - chest from each end of said auxiliary exhaust-passage, an auxiliary exhaust-port entering said valve-chest from said auxiliary exhaust - passage between said outlet-ports, a main valve controlling said main ports and provided with a single auxiliary port to connect said exhaust-ports, an auxiliary piston-valve located within said valve-chest and operating said main valve, said auxiliary piston-valve being provided with a central steam-chamber and a steam-passage at each end thereof connecting said central steam-chamber with the ends of said valve-chest.
6. In an engine, a valve-chest provided with two main inlet-ports and a main exhaust-port, an auxiliary exhaust - passage extending lengthwise of said valve-chest, an auxiliary outlet-port connecting said valve-chest with each end of said auxiliary exhaust-passage, an auxiliary exhaust-port entering said valve-chest from said auxiliary exhaust - passage between said auxiliary outlet-ports, a main valve controlling said main ports, an auxiliary piston-valve located within said valve-chest and operating said main valve, said auxiliary piston-valve being provided with a central steam-chamber, a steam-passage at each end thereof connecting said central steam-chamber with the ends of said valve-chest, and a port at each end of said auxiliary piston-valve connecting said auxiliary outlet-ports with the ends of said valve-chest.
7. In an engine, a main cylinder, a piston therein, a valve-chest provided with two main inlet-ports and a main exhaust-port, said ports communicating with said cylinder, two auxiliary outlet-ports and an auxiliary exhaust-port, said auxiliary outlet-ports and said auxiliary exhaust-port entering said valve-chest from a common passage; a main valve controlling said main ports and provided with a single auxiliary port to connect said exhaust-ports, an auxiliary piston-valve located within said valve - chest and operating said main valve, and mechanism operatively connecting said piston and auxiliary piston - valve to move said main valve and auxiliary piston-valve through a portion of their travel and open connection from one end of said valve-chest through one of said auxiliary outlet-ports and through said auxiliary exhaust-ports to said main exhaust-port, while closing the other of said auxiliary outlet-ports.
8. In an engine, a main cylinder, a piston
- therein, a valve-chest provided with two main inlet-ports and a main exhaust-port, said ports communicating with said cylinder, an auxiliary exhaust-passage extending lengthwise of said valve-chest, an auxiliary outlet-port entering said valve-chest from each end of said auxiliary exhaust-passage, an auxiliary exhaust-port entering said valve-chest from said auxiliary exhaust-passage between said auxiliary outlet-ports, a main valve controlling said main ports and provided with a single auxiliary port to connect said exhaust-ports, an auxiliary piston-valve located within said valve - chest and operating said main valve, and mechanism operatively connecting said piston and auxiliary piston-valve to move said main valve and auxiliary piston-valve through a portion of their travel and open connection from one end of said valve-chest through one of said auxiliary outlet-ports and through said auxiliary exhaust-ports to said main exhaust-port, while closing the other of said auxiliary outlet-ports.
9. In an engine, a valve-chest, an auxiliary piston - valve located therein and provided with a head at each end thereof, said heads each provided with a recess opening therein from one end and with an annular steam-passage extending around the periphery thereof and connected by a passage with said recess.
10. In an engine, a valve-chest provided with two main inlet-ports and a main exhaust-port, two auxiliary outlet-ports and an auxiliary exhaust-port, said auxiliary outlet-ports and auxiliary exhaust - port entering said valve-chest from a common passage, a main valve controlling said main ports and provided with a single auxiliary port to connect said exhaust-ports, and an auxiliary piston-valve located within said valve-chest and provided with a head at each end thereof, said heads each provided with a recess opening therein from one end and with an annular steam-passage extending around the periphery thereof and connected by a passage with said recess, said auxiliary piston-valve operating said main valve and acting as a switch to alternately control the auxiliary exhaust from opposite ends of said auxiliary passage.

In testimony whereof we have hereunto set our hands in presence of two subscribing witnesses.
